UNITED STATES PATENT OFFICE.

HARRY I. CLULEE, OF WALLINGFORD, CONNECTICUT, ASSIGNOR TO R. WALLACE & SONS MANUFACTURING COMPANY, OF SAME PLACE.

DESIGN FOR A SPOON OR FORK HANDLE.

SPECIFICATION forming part of Design No. 21,692, dated July 5, 1892.

Application filed May 23, 1892. Serial No. 434,112. Term of patent 3½ years.

To all whom it may concern:

Be it known that I, HARRY I. CLULEE, of Wallingford, in the county of New Haven and State of Connecticut, have invented a new 5 Design for a Spoon or Fork Handle; and I do hereby declare the following, when taken in connection with accompanying drawing, to be a full, clear, and exact description of the same, and which said drawing constitutes part 10 of this specification, and represents a face view.

This invention relates to a design for the ornamentation of the handles of spoons and forks; and the design consists in the configuration and ornamentation as shown in the 15 accompanying illustration.

On the face of the handle is the representation of Masonic emblems, representing in succession the square and compass, the triangle 20 inclosing an eye, a keystone inclosing a circle, a Maltese cross with the representation on its

face of a circular center inclosing a cross and crown, a star, and an hour-glass. Surrounding these emblems is the representation of scroll or rococo work, forming a border around the handle. The outline of the handle corresponds to the shape of the scroll-work, and on the face of the handle, between the emblems and the bowl, is the representation of a succession of scroll-work in relief, and as shown 25 in the accompanying illustration.

I claim—

The design for the handles of spoons and forks, as herein described, and shown in the 30 accompanying illustration.

In testimony whereof I have signed this specification in the presence of two subscribing witnesses.

HARRY I. CLULEE.
